UNITED STATES PATENT OFFICE.

CHARLES PETERS, OF NAMPA, IDAHO.

ROPE-SOCKET.

SPECIFICATION forming part of Letters Patent No. 761,396, dated May 31, 1904.

Application filed July 22, 1903. Serial No. 166,611. (No model.)

To all whom it may concern:

Be it known that I, CHARLES PETERS, a citizen of the United States, residing at Nampa, in the county of Canyon and State of Idaho, have invented a new and useful Rope-Socket, of which the following is a specification.

This invention relates to devices for coupling the ends of ropes to drilling-tools or other fixtures, and is applicable more particularly to well-drilling apparatus, but which may also be employed wherever it is desired to couple a rope or cable to a chain or other device.

The invention consists in a tapered socket screw-threaded at its larger end and carrying means for the attachment of the drill-tool at its smaller end, two or more opposing reversely-tapered clamp-plates having inwardly-extended teeth and engaging the interior of the socket by their exterior surfaces and supporting the rope between them, and a head member adapted to loosely engage the cable and also engaging the screw-threads of the tapered socket, whereby means are provided for forcing the clamp-plates into the socket and contracting them upon the rope or cable.

Other novel features of the invention will be disclosed in the annexed description and specified in the claims following.

In the drawings illustrative of the invention, Figure 1 is a vertical section of the device. Fig. 2 is a transverse section on the line 2-2 of Fig. 1. Fig. 3 is a detail view illustrating a slight modification.

The outer socket is represented at 10, with means, such as an eye 10^a, at its lower end for coupling the drilling tool, chain, or other device. The socket flares outwardly from the eye end, as illustrated, and is provided with an interior screw-thread 11 at its larger end, 40 with which a hollow sleeve or head 12 engages, the head having means, such as apertures 12^a, for the connection of a wrench or other means for rotating it, whereby the head may be adjusted in the socket. Within the socket are disposed two opposing tapered segmental plates 13 13^a, the two plates when combined forming a tapered divided sleeve, as shown. Extending from the interiors of the plates 13 13^a are spurs 14, as shown.

50 The rope or cable is indicated at 15 and will

be enclasped at its end by the plates 13 13^a, with the spurs extending into the cable to firmly clamp it between the plates.

When the device is to be used, the head 12 will be passed over the end of the rope or cable and the plates 13 13^a placed upon opposite sides of the end of the cable below the head 12. The plates 13 13^a will not meet at their adjacent edges, as indicated in Fig. 2, so that when inserted into the socket with the cable between them and the head member screwed "home" in the socket the plates will have ample room in which to be contracted around the cable when forced downward into the tapered socket. By this means the cable will be very firmly clamped between the plates and rigidly united to the socket member.

While two of the tapered plate members 13 13^a are shown, I do not desire to be limited to this number, as a change in this particular would not be a departure from the principle of the invention.

The device may be constructed to fit any-sized rope or cable and will form a very efficient implement for the various purposes for which similar devices are employed. Its extreme simplicity and ease of application and great strength of "grip" will make it a very efficient and valuable device.

Where ropes of smaller diameter than the socket are to be employed in connection therewith, I prefer to use an auxiliary sleeve 16, which may be placed within the head 12, and said sleeve is provided with a flange 17, extending under the head and engaging the plates 13 13^a. This is plainly illustrated in Fig. 3.

Having thus described my invention, what I claim is—

1. A clamp comprising a socket member flared toward one end with tool-attaching means carried by its smaller end and internally screw-threaded at its larger end, a plurality of opposing clamp members correspondingly tapered and adapted to enclasp a cable and to fit in said flared socket member, said clamp members having inwardly-extending spurs to engage the cable, and a sleeve slidable on the cable and having an externally-screw-threaded reduced end adapted to engage with said threaded socket and having a shoul-

der adapted to abut against the outer edge of the socket with the inner edge of its reduced end abutting against the outer edges of the clamp members to exert a longitudinal force upon said tapered clamp members to move them forcibly into said socket.

2. A clamp comprising a socket member flared toward one end, a plurality of clamping members having inwardly-extending cable-engaging spurs adapted to penetrate the cable and hold said clamp members firmly in connection therewith, a sleeve loosely engaging

said cable and adapted to engage the flared end of the socket member, and a removable bushing disposed in said sleeve and having an outwardly-projecting peripheral flange arranged between the sleeve and clamp members. 15

In testimony that I claim the foregoing as my own I have hereto affixed my signature in the presence of two witnesses.

CHARLES PETERS.
